CASH CONTROLLING AND REGISTERING AND CHANGE-RETURNING APPARATUS.

1,092,054.

Specification of Letters Patent. Patented Mar. 31, 1914.

Application filed March 7, 1913. Serial No. 752,642.

To all whom it may concern:

Be it known that I, EDOUARD JANIK, a citizen of the French Republic, residing at No. 20 Rue de Mogador, Paris, France, have 5 invented certain new and useful Improvements in Cash Controlling and Registering and Change-Returning Apparatus, of which the following is a specification.

This invention has for its object to provide 10 an improved cash controlling and registering and change returning apparatus of the kind described in the specification of my earlier U. S. Letters Patent No. 952,526 dated 22d March, 1910. In the apparatus 15 described in the said specification, the ejectors *e* provided with lateral pins *p* are arranged to rest by means of the said pins in open bearings *q* on a connecting bar *f* which forms a rigid frame with a parallel 20 transverse bar *r* and pusher rack bars *g*. In that construction the adjustment of the positioning of the adjusting lever *c* is effected by means of the operating shaft 99 through the medium of levers acting upon 25 separate shafts and by means of cam disks. Now all those parts are dispensed with in the improved apparatus of the present invention, wherein improved means are provided for effecting the adjustment of the adjusting levers directly from the shaft 99.

The present invention is illustrated by way of example in the accompanying drawings, in which:—

Figure 1 is an elevation, and Fig. 2 is a 30 plan of a construction of apparatus embodying the present improvements.

As shown, the bar *f* carrying the open

bearing *q* is provided under the ejectors *e* with compression springs *z* having a tendency to push the adjusting levers *c* in an upward direction. These levers *c* are thus caused to bear each with a projection *c'* provided on it against a pusher cam *x* fixed on the shaft 99. When the stepped disks have been placed into position (which placing causes the shaft 99 to rotate in the direction of the arrow), the cams *x* will release the adjusting levers *c*. The springs *z* will then push the levers *c* against the stepped disks and can therefore determine the vertical adjustment of the latter.

Having now described my invention what I claim as new and desire to secure by Letters Patent is:—

In a crank-operated cash controlling and registering and change returning apparatus, the combination with a slide for ejecting the change, slide blocks for actuating said ejecting slide, guide levers for said slide blocks, stepped disks for vertically adjusting the position of said guide levers, an operating shaft, springs having a tendency to raise said guide levers, and cam disks on said operating shaft for freeing said guide levers from the action of said springs during the positioning of said stepped disks.

In testimony whereof I have signed my name to this specification in the presence of two subscribing witnesses.

EDOUARD JANIK.
